(No Model.)

W. H. WOOD.
GUIDE FOR STEAM HAMMERS.

No. 537,333.

Patented Apr. 9, 1895.

UNITED STATES PATENT OFFICE.

WILLIAM H. WOOD, OF MEDIA, PENNSYLVANIA.

GUIDE FOR STEAM-HAMMERS.

SPECIFICATION forming part of Letters Patent No. 537,333, dated April 9, 1895.

Application filed November 20, 1894. Serial No. 529,403. (No model.)

To all whom it may concern:

Be it known that I, WILLIAM H. WOOD, a citizen of the United States, and a resident of Media, in the county of Delaware and State 5 of Pennsylvania, have invented certain new and useful Improvements in Guides for Steam-Hammers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of so much 15 of a "single standard" steam-hammer as is necessary to illustrate my improvement. Fig. 2 is a transverse sectional view through the same, on line $x-x$ in Fig. 1. Fig. 3 is a vertical sectional view through the middle of the 20 standard, on line $y-y$ in Fig. 1. Fig. 4 is a cross section of one of my improved automatically adjustable guides; and Fig. 5 is a rear elevation of the same.

Like letters of reference designate corresponding parts in all the figures.

This invention has relation to steam hammers, and consists in an improved construction of the guides, which is applicable with equal facility and advantage to both "single" 30 and "double standard" hammers. In the present instance, I have shown my improved automatic guides as applied to a "single standard" hammer; but their application and adjustment to a "double standard" involves 35 no departure from the construction herein-after to be described, and will be readily understood by all persons familiar with the art to which my invention relates.

Referring to the accompany drawings, the 40 reference-letter A designates the standard of a steam hammer, and B the vertically reciprocating hammer; the steam cylinder being shown at C and the anvil at D. The upper part of the standard, which is recessed, as 45 usual, to make room for the vertically reciprocating hammer, is cast with two outside hubs, E E, on each side, which are in vertical alignment with each other, and recessed on their inner sides, facing the hammer recess, to 50 form circular chambers or recesses, $e e$, which have central bores or apertures, f , bored

through the outer wall of each hollow hub E, for the purpose hereinafter set forth.

Arranged within the recessed upper part of the standard, one on each side of the hammer, are the guides F, the shape of which is clearly illustrated in Figs. 2, 4 and 5. Each of these guides consists of a rectangular plate or casting, having a slightly raised or projecting central flange, F', on its back, which 55 will fit into a corresponding and contiguous planed groove or depression f' in the hammer recess of the standard A, (one on each side.) This guide is also provided with two cast projecting circular bosses, G G, which will fit 60 snugly within the circular recesses $e e$ of the projecting hubs E. The parallel sides of each guide F are also planed off smooth so as to fit within its appropriate recess in the standard, so that the guides may have a limited for- 65 ward and back movement or play in their re- 70 spective side recesses.

The circular guide-bosses G do not fill out the hollow hubs within which they are inserted, but leave an open space back of each 75 boss, into which is inserted a stiff spiral spring H, the operation of which is to force or impel the guide out from its recess in the standard and up against the adjacent and impinging side of the hammer; but this outward or lat- 80 eral play of the guide is limited and checked by a screw-threaded pin or bolt I, the inner end of which is screwed through the center of the boss G into the body of the guide, while its outer end, after passing centrally and 85 loosely through the coiled spring H, and through the central aperture f in the hub, has placed upon it a spring-washer i and nut j . This nut is screwed up tightly against the washer; and in order to prevent it from jar- 90 ring off, on account of the constant shaking and vibration to which the standard is sub- 95 jected while the hammer is in operation, I prefer to fasten the nut j by any one of the well-known devices (or so-called nut-locks) for preventing nuts from jarring off, so that the nut will always be held effectually and permanently in place.

The opposite sides or faces of the movable, spring-actuated guides F F are grooved, as 100 usual, to form two V-shaped ribs or projections, which fit into corresponding grooved

ways in the adjacent sides of the hammer, and thus serve to guide this true up-and-down on its strokes. By means of the rearwardly projecting bosses G, in combination 5 with the recessed hubs on the sides of the standard, and the coiled springs H within said hubs, the guides on both sides are made sufficiently yielding, or have sufficient "give," to accommodate or adjust themselves to any 10 irregularity or unevenness of stroke in the working of the hammer. In other words, this spring adjustment virtually and practically gives the same advantages as a flexible piston-rod for the hammer, without any of its disadvantages. The vertical alignment of the 15 hammer strokes will always be perfect, and all lateral strain upon either the piston rod, hammer, or frame is avoided by the lateral elasticity or yielding of the guides, which, as 20 before stated, will adjust themselves automatically to the lateral vibrations or deviations of the hammer, which always exist to a greater or lesser extent, and thus avoid fracturing or breakage of the standard, as well as 25 straining and breaking of the piston-rod.

Having thus described my invention, I claim and desire to secure by Letters Patent of the United States—

In a steam hammer, the combination with the reciprocating hammer and the frame or 30 standard within which it works, formed with opposite vertical grooves, and with outwardly extending centrally apertured hubs on opposite sides, of the guides F, provided with vertical flanges on their outer sides fitting in the 35 grooves in said frames and with circular bosses fitting into said hubs, the bolts H passing through said hubs and engaging with the guides, the washers and nuts on said bolts, and the coiled springs interposed between the 40 said guides and the ends of the hubs, substantially as described.

In testimony that I claim the foregoing as my own I have hereunto affixed my signature in presence of two witnesses.

WILLIAM H. WOOD.
